UNITED STATES PATENT OFFICE.

BENJAMIN H. THWAITE, OF WESTMINSTER, LONDON, ENGLAND.

APPARATUS FOR WASHING IRON-BLAST-FURNACE GASES.

No. 896,175.

Specification of Letters Patent.

Patented Aug. 18, 1908.

Application filed June 23, 1905. Serial No. 266,645.

To all whom it may concern:

Be it known that I, BENJAMIN H. THWAITE, subject of the King of Great Britain and Ireland, and residing at Westminster, London, England, have invented 5 certain new and useful Improvements in Apparatus for Washing Iron-Blast-Furnace Gases, of which the following is a specification.

This invention relates to apparatus for washing blast furnace gases, and especially to so called box-washers comprising boxes containing water and divided by partitions which depend from the top of each box below 15 the water level so that the gases which are drawn or forced through the washer are caused to work their way under each partition and thus come into direct contact with the water.

The object of the present invention is to improve this type of apparatus so that the gases are more thoroughly washed and cooled and rendered more fit for use in gas engines and also to enable some of the heat 25 removed from the gases passing through the washer to be utilized in softening water.

According to the present invention each partition is fitted with a movable screen or perforated plate just beneath its lower edge 30 so that the gases are compelled to flow in small streams or jets, the screens being adapted to be swung about pivots or hinge pins by means of levers.

In the preferred form of the apparatus it is 35 constructed as a series of compartments so that the gases are compelled to pass in succession through water a number of times and the whole washer is provided with a water seal or trough to permit cleaning or removal 40 of deposits even during operation, and further the top of the apparatus is constructed as a tank so that the water therein not only aids in cooling the gases in the washer but may be heated to a temperature that will 45 suffice to effect the separation of the lime from the water which latter may be employed for circulation in the engine jacket or for other purposes.

In the accompanying drawings, Figure 1 50 is a transverse sectional elevation of a double box-washer according to the invention. Fig. 2 being a plan corresponding thereto, Fig. 3 is a transverse sectional elevation of a single box-washer according to the invention, 55 Fig. 4 is a longitudinal sectional elevation on line X—Y, Fig. 2.

In carrying out the invention the main casing or box, *a*, is divided by partitions, *b*, into a number of compartments or chambers, *c*. Each partition, *b*, dips below the water level and adjacent to or in each opening is mounted a wire gauze screen or perforated plate, *d*, carried by brackets, *e*, on a shaft or rod, *f*, one end of which passes through the outer side 65 wall of the main casing, *a*, and is formed with or as a hand lever, *g*, so that the screen, *d*, can be oscillated.

The main box or casing, *a*, is mounted in a trough or water seal, *h*, and some or all of the 70 separate compartments are provided with side openings for instance as indicated at *i*, to enable matter deposited in the chambers to be removed without stopping the operation of the apparatus.

The water level in the apparatus is determined by the position of an overflow pipe, *k*, (Fig. 4) fitted to one of the chambers, the pipe being provided with a hydraulic seal, *l*.

Obviously a single series of chambers may be 80 used in which case the trough, *h*, need only be along one side as shown in Fig. 3 or a double series may be used as indicated in Figs. 1 and 2 the gases entering the first chamber through an inlet pipe, *m*, and then 85 passing through the chambers in succession as indicated by the arrows in Figs. 1 and 2 issuing from the last chamber by an outlet pipe, *n*.

By combining or arranging a number of 90 box-washers as described as many stages of temperature reduction may be arranged as there are washers, for instance in the first the temperature of the gas may be reduced from say, 500° to 250° F. and in the second from 95 250° to 150° F.

In order to further reduce the temperature of the gases, and to do so in such a way that the heat may be utilized, the top of the main casing, *a*, may be made in the form of a shallow tank or closed vessel, *o*, in which hard water may be heated to a temperature that will be sufficient to effect the separation of the lime from the water, so that such water may be used for circulation in the gas engine 105 jacket, or soft water may be treated for steam generating purposes. The top of the casing, *a*, forming the bottom of the tank, *o*, may be made of suitable form and material to present considerable heat exchanging surface. The tank is fitted with suitable inlet and outlet pipes, *p q*.

In order to secure more effective water scrubbing of the gases, the water in the box washers is allowed to become highly saturated with the deposited solid matter, so that its density is increased and with it its frictional efficiency. The degree of dust separation from the gas is a function of the resistance set up and this resistance is increased as the water becomes charged with the water separated from the gas. In order to increase the frictional resistance a certain portion of liquid tar may be added to the water in the box washers.

By providing the perforated plates or gauze screens in the partitions and adapting them to be agitated the gas is compelled to flow in equal volumetric increments through the perforations and cannot flow through in big bubbles.

Having thus described my invention what I claim as new and desire to secure by Letters Patent is:—

1. A box washer comprising a main casing, water in said casing, partitions dividing the casing into compartments, and having openings below the water level, hinged screens adjacent to said openings and means for agitating said screens adapted to be operated from outside said casing.

2. A box washer comprising a main casing, water in said casing, partitions dividing the casing into compartments, and having openings below the water level, hinged screens ad-

jacent to said openings means for agitating said screens adapted to be operated from outside said casing, a water trough alongside the main casing and openings in the side and near the bottom of the casing communicating with said trough for the purpose hereinbefore set forth.

3. A box washer comprising a main casing, water in said casing, partitions dividing the casing into compartments, and having openings below the water level, hinged screens adjacent to said openings means for agitating said screens adapted to be operated from outside said casing, a water outlet pipe fitted to one of the compartments and a hydraulic seal for said pipe substantially as and for the purpose hereinbefore set forth.

4. A box-washer comprising a main casing, water in said casing, partitions dividing the casing into series of compartments and having openings below the water level, screens adjacent said openings, means operable from outside the casing for agitating said screens, and a water tank on the top of said casing, substantially as and for the purpose set forth.

In testimony whereof I have hereunto set my hand in presence of two subscribing witnesses.

B. H. THWAITE.
